FORK OR THE LIKE

Earl B. Pardon, Newburyport, Mass., assignor to Towle Manufacturing Company, Newburyport, Mass., a corporation of Massachusetts

Application October 11, 1955, Serial No. 38,324

Term of patent 14 years

(Cl. D54—12)

Fig. 1 is a front elevation of the fork;

Fig. 2 is a side view of Fig. 1;

Fig. 3 is an end view of the tip of the handle showing a decorative inset therein;

Fig. 4 is a cross-section to larger scale intermediate the tip and bolster;

Fig. 5 is a cross-section to larger scale at the bolster; and

Fig. 6 is a fragmentary rear elevation of the handle of the fork broken away between the tip and bolster.

I claim:

The ornamental design for a fork or the like, substantially as shown.
